UNITED STATES PATENT OFFICE.

OWEN S. HALL, OF RED LODGE, MONTANA.

MOLD.

1,172,451.

Specification of Letters Patent. Patented Feb. 22, 1916.

Application filed April 28, 1915. Serial No. 24,462.

To all whom it may concern:

Be it known that I, OWEN S. HALL, a citizen of the United States, residing at Red Lodge, in the county of Carbon, State of Montana, have invented certain new and useful Improvements in Molds; and I do hereby declare the following to be a full, clear, and exact description of the invention, such as will enable others skilled in the art to which it appertains to make and use the same.

This invention relates to molds and particularly to the type adapted for use in the production of tubular concrete blocks.

The object of the invention resides in the provision of a mold of the type named through the instrumentality of which a plurality of tubular blocks may be formed in such manner that when the blocks are removed from the mold they may be arranged end to end in interlocking relation to form a continuous tubular member for use as a culvert.

A further object of the invention resides in the provision of a mold of the type named which can be easily set up and knocked down and which will produce a high grade of work.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a side view of a mold constructed in accordance with the invention and adapted for use in forming the intermediate sections of a concrete culvert of the type set forth and claimed in my copending application filed April 14, 1914, Serial No. 831,769; Fig. 2, a plan view of what is shown in Fig. 1; Fig. 3, a vertical section of what is shown in Fig. 1; Fig. 4, a transverse section of what is shown in Fig. 1; Fig. 5, a horizontal section of what is shown in Fig. 1; Fig. 6, a perspective view of one of the partitions of the mold; Fig. 7, a perspective view of a fragment of the base of the mold, and Fig. 8, a perspective view of a fragment of the collapsible core employed in the mold.

Referring to the drawings the improved mold is shown as comprising a base member 10 having ledges 11 suitably secured on the upper side thereof along its respective side edges. These ledges 11 are provided with corresponding grooves 12 formed in their inner faces. These grooves are equally spaced from each other and engaged in corresponding grooves are the lower side edges of division plates A. Each of these division plates A is provided with a core receiving opening 13 and each plate further embodies offset lower and upper ends 14 and 15 and an intermediate connecting portion 16, said portion 16 being inclined downwardly. Each of the division plates A is further provided with a plurality of laterally extending eye members 17.

The improved mold further comprises lower side members 18 each of which is provided with upper and lower longitudinal flanges 19 and 20 respectively, the latter resting upon the upper edges of the ledges 11, while the former are provided at spaced points with slots 21. Each of the lower side members 18 is provided with openings 22 through which are engaged respective eye members 17. A wedge 23 is then engaged through each eye member 17 and in this manner the lower side members 18 are secured in place.

The mold further comprises upper side members 24 each of which is provided with upper and lower flanges 25, the latter resting upon the upper flanges 19 of the lower side members 18. Secured to each upper side member 24 is a plurality of fingers 26 which project through openings in the lower flanges 25 and are detachably engaged through respective slots 21 to interlock the upper and lower side members. Each of the upper side members 24 is further provided with openings 27 through which are engaged respectively certain of the eye members 17. Wedges 28 are passed through the eye members 17 which project through the openings 27 and in this way the upper side members 24 are detachably secured to the division plates A. It will be noted that the upper edges of the upper side members 24 are disposed in spaced relation to provide a suitable opening for the introduction of cement or other plastic material into the mold.

The mold further comprises a core ele-

ment B of the collapsible type, said element when in place being engaged through the core, receiving openings 13. This core B is formed of suitable sheet metal bent into substantially cylindrical form with its side edges disposed in spaced relation. Secured to the inner side of the core B adjacent each side edge thereof is a longitudinal angle iron 29. Pivottally connected to each angle iron 29 is a plurality of levers 30 the inner ends of which are pivotally connected to a common operating bar 31. When the core B is collapsed corresponding levers 30 will be disposed at an angle to each other. If it is desired to expand the core to its limit the bar 31 is moved longitudinally until corresponding levers 30 are disposed in longitudinal alinement.

In the use of the mold the upper side members and the core are first removed and the material is introduced between the division plates up to the lower edge of the openings 13. The core B is then placed through the openings 13 and spread by operating the bar 31 until it fits snug against the walls of the openings 13. Additional material is then introduced into the mold up to the top of the bottom side members 18. The upper side members 24 are then secured in place and the balance of the material introduced into the mold.

It will be noted that the top portion of the core B is somewhat thicker than the side portion so that in collapsing the spring

action will come in the sides of the core and keep the latter from pinching at the top and bottom when withdrawn. In the present instance I reach this end by securing a supplemental plate C across the top of the core and riveting the edges of this plate 40 to the side portions of the core. Suitable reinforcing ribs D are secured to the inner side of the core, same being shown in this instance as angle irons.

While I have illustrated and described one form of carrying my invention into practice it will be obvious that various changes in size, proportion, shape and arrangement can be resorted to without departing from the scope of the invention as set forth in the appended claim.

What is claimed is:—

In a mold of the class described, the combination of a plurality of spaced division plates having offset upper and lower portions and a downwardly inclined intermediate portion connecting said lower and upper portions, said plates being further provided with aligned core receiving openings, side members detachably interlocked with said plates, and a collapsible core engaged through the openings in the plates.

In testimony whereof, I affix my signature, in the presence of two witnesses.

OWEN S. HALL
